HAIR WAVING APPARATUS

Macia Smith Mabie, San Francisco, Calif.

Application April 30, 1934, Serial No. 723,160

4 Claims. (Cl. 132—33)

This invention relates to improvements in hair waving apparatus of the kind utilized in beauty parlors for the commercial waving of human hair.

5 An object of my invention is to provide improved hair waving apparatus which is capable of being conveniently manipulated and controlled by an operator to secure a desirable waving effect.

10 A still further object of my invention is to provide an improved and novel heater for use in waving human hair, embodying a construction which is relatively simple and inexpensive to manufacture, and one which is capable of being advantageously employed in producing waving effects in strands of hair wound upon an internal electrically heated spindle.

15 Other objects more or less apparent will present themselves or will be specifically pointed out in the description of my invention which is to follow.

In the accompanying drawing:

20 Fig. 1 is a top plan view of the hair clamping part of a heater embodying my invention, showing the hinged cover in an open position;

25 Fig. 2 is a top plan view similar to Fig. 1, showing the hair clamping bars in separated positions;

Fig. 3 is an end view of the same;

30 Fig. 4 is a plan view of an internal electrically heated spindle which is adapted to be held in an operative position by the part of the device illustrated in Figures 1, 2 and 3;

35 Fig. 5 is an end view of the spindle showing the operating handle thereon; and

Fig. 6 is an end view of the spindle, showing the same operatively mounted in the hair clamping part of the device.

40 A hair waving heater of the kind embodying my invention is illustrated in Figs. 1 to 6 inclusive, wherein the numerals 20 and 21 designate two rubber covered hair clamping bars. The bars are pivotally connected together at ends thereof by means of a pin or rivet 22. Secured to the bar 21 are hinge members 23, which together with a rod 24 serve to pivotally attach a hinged cover or shield 25 to the said bar. Secured to a side of the bar 20 at opposite ends thereof are flanges 26 which project inwardly and are intended to prevent any hairs clamped between the bars 20 and 21 from becoming lodged in the end structures of the device. The flanges 26 also serve to maintain the strand of hair in such a position that it is properly engaged by the resilient rubber coverings on the bars 20 and 21, thereby insur-

ing the firm gripping of all of the various hairs of the strand, so that no pulling effect is imparted to any particular part of the said strand while the waving process is being carried out. So as to maintain the bars 20 and 21 in firmly clamped positions when a strand of hair is held therebetween, I have rigidly and centrally secured a blade 27 to the free end of the bar 20 in such a manner that it projects inwardly for a considerable distance beyond the inner face of the said bar. The 10 adjacent free end of the bar 21 is centrally slit so as to provide two spaced prongs 28 between which the blade 27 may become lodged. Through the frictional engagement of the prongs 28 with the opposite sides of the blade 27, the two 15 bars 20 and 21 may be held in a securely clamped position with a strand of hair firmly held between the rubber coverings thereon. In order to conveniently separate the free ends of the bars 20 and 21, and to readily release the blade 27 of 20 the bar 20 from the two prongs 28 of the bar 21, I have pivotally attached a finger pressed lever member 29, as at 30, to the bar 20. The lever member is provided with an outwardly projecting thumb piece 31 at one end, and with an inwardly 25 extending flanged part 32 at its opposite end. A spring 33, extending around a stationary pin 34 carried by the bar 20 and with its free end engaging with the thumb piece 31, exerts an inward pressure upon the thumb piece end of the lever member, thereby normally returning the inwardly 30 extending flange 32 to a position in which it engages with the inner surface of the bar 21 when the latter is positioned in close proximity to the bar 20. When the thumb piece 31 is pressed outwardly, the flanged part 32 of the lever member forces the free end of the bar 21 in a direction away from the free end of the bar 20, thereby 35 causing the release of the blade 27 from the prongs 28.

40 In ordinary practice, after the strand of hair is properly clamped between the two bars 20 and 21, a spindle 35 is employed to wind the hair upon, prior to the heating and curling or waving operation. So as to hold the extreme ends of the hair in position, prior to its being wound upon the spindle, I have pivotally attached an end of an arcuate member 36 to the said spindle. The ends of a strand of hair are held between the arcuate member 36 and the spindle 35 when 45 the said spindle is turned to cause the winding of the hair thereon. The spindle is hollow and is provided therein with an electrical heater which is supplied with a current of electrical energy by a cord 19. One end of the spindle is 50 55

preferably formed with a socket within which two terminals of the internally disposed electrical heater is connected, and the cord '19' is provided with a plug which is adapted to detachably fit inside the socket to make the proper electrical connection. The opposite end of the spindle is provided with a finger piece 37 which permits the convenient turning of the said spindle to cause the winding of a strand of hair thereon. 10 The two opposite ends of the spindle are provided with suitable friction rings 38 which are adapted to become engaged with the upwardly disposed parts 39 of a spring clip secured to opposite ends of the bar 20. The opposed parts 39 of the 15 spring clip engaging with the friction rings 38 of the spindle normally prevent the latter from unwinding after the hair is wound thereon. The friction rings, as illustrated on the drawing, are preferably made of rubber or other suitable material. It is also within the purview of my invention to make the friction rings 38 of metal with their circumferential surfaces corrugated or otherwise serrated. After the hair is wound upon the spindle 35 and the latter is mounted 20 between the spring clips 39, the shield or cover 25 is placed over the same, as illustrated in Fig. 3 by the dotted lines.

While I have described the illustrated embodiment of my invention with considerable particularity, this is done by way of illustration only and it is obvious that many other embodiments will readily occur to those skilled in this art, and I therefore do not limit my invention to the precise details shown and described, but claim all 30 embodiments coming within the scope of the appended claims.

Having described my invention what I claim is:

1. In a hair waving device, a pair of hair clamping bars pivoted to each other at one end, one 40 of the bars at its free end having an inwardly

protruding blade, the other of the bars at its free end having spaced prongs with which the blade is adapted to frictionally engage to maintain the bars in clamping positions alongside one another, and a lever member pivoted on one of the bars for separating the bars. 5

2. In a hair waving device, a pair of hair clamping bars pivoted to each other at one end, means for releasably holding the bars in clamped positions, a pair of spaced spring clips mounted above the bars, an electrically heated spindle removably grasped by the clips, the said spindle having one or more friction rings thereon with which the spring clips engage to normally prevent the spindle from turning. 10

3. In a hair waving device, a pair of hair clamping bars pivoted to each other at one end, means for releasably holding the bars in clamping positions adjacent one another, a pair of spaced spring clips mounted above the bars, an electrically heated spindle removably grasped by the clips, the said spindle having one or more friction rings thereon with which the spring clips engage to normally prevent the spindle from turning, and a cover hinged to one of the bars 20 and adapted to overlie the spindle. 15

4. In a hair waving device, a pair of hair clamping bars pivoted to each other at one end, means for releasably holding the bars in clamping positions adjacent one another, the said means comprising a blade carried by one bar and a pair of prongs carried with the other bar and with which the blade is adapted to frictionally engage, a pair of spaced spring clips mounted above the bars, an electrically heated spindle removably held by the clips, the said spindle having one or more friction rings thereon with which the spring clips engage to normally prevent the spindle from turning, and a cover hinged to one of the bars 30 and adapted to overlie the spindle. 35
